R. E. MANLEY

PORTABLE GARAGE LIGHT

Filed June 8, 1923

Inventor:

Robert E. Manley
By Church & Church
Atorneys.

UNITED STATES PATENT OFFICE.

ROBERT E. MANLEY, OF YORK, PENNSYLVANIA.

PORTABLE GARAGE LIGHT.

Application filed June 8, 1923. Serial No. 644,209.

To all whom it may concern:

Be it known that I, ROBERT E. MANLEY, a citizen of the United States, residing at York, in the county of York and State of Pennsylvania, have invented certain new and useful Improvements in Portable Garage Lights; and I do hereby declare the following to be a full, clear, and exact description of the same, reference being had 10 to the accompanying drawings, forming part of this specification.

This invention relates to a portable light primarily intended for use in a garage. The object of the present invention is the 15 provision of a garage light of such type as to be more convenient in use than any existing forms. A further object of the present invention is the provision of a standard and lamp-carrying arm pivoted thereto and having at the pivotal point an attachment socket so that an electric tool, 20 a drill for example, may be used in connection with the light.

It is customary at the present time to use 25-in garages what is known as a trouble light which consists merely in a lamp socket having a large wooden handle provided with a hook on one end to hang the light to any 30 convenient point and having a wire protector over the lamp so that it may be laid on the floor if desired.

The present light obviates the use of the trouble light and permits the throwing of the rays from the lamp in the position most 35 convenient to the mechanic, being so arranged for example as to extend the lamp-carrying arm through the window or door of a sedan or coupe so as to throw the light at any part desired, in transmission, or 40 brake band work, for example.

In the drawings,—

The figure is a perspective of the light.

The base 10 is preferably a casting of such weight as to conveniently hold the 45 lamp upright in the most extended position of the lamp-carrying arm. The tube 11 is threaded so as to fit in the socket 12 of the casting and carries within it one

or more sections 14 and 15 telescoping in the usual manner to form a standard and 50 having set screws to hold the standard at the desired height. At its upper end the telescoping standard carries a head 17 preferably serrated as at 18 to engage corresponding serrations on the hollow barrel 55 member 20 pivoted to the head 17 and adjustably secured thereon by means of the small hand wheel 21.

An arm 25 is secured to the barrel 20 in any desired manner and is bent through an 60 angle of 90° as at 26 near its end which end carries a lamp socket 27. The lamp 28, reflector 29, and protector 30 are all of the usual type forming no part of the present invention. In one end of the hollow barrel 65 20 an attachment socket 32 is provided so that the plug from a tool may be inserted therein, the flexible connector 34 passing through the barrel 20 to the attachment socket and through the hollow arm 25 to 70 the lamp socket 27.

The arm 25 is preferably of such length that when the standard is completely telescoped the lamp socket 27 will be in close proximity to the base 10 this feature being 75 very convenient for throwing the light under the chassis.

What I claim is:

1. In a portable electric light, a base, a telescoping standard connected to said base, 80 an arm, a lamp socket carried thereby, means for pivotally connecting said arm and said standard, an attachment socket supported by said standard and movable with said arm, and a flexible conductor electrically connected to said sockets.

2. In a garage light, a barrel, a hollow arm secured to said barrel, an attachment socket in one end of said barrel, a base, a standard rising therefrom, means for rotatably mounting said barrel on said standard, and means for adjustably securing said barrel in any desired angular relation with respect to said standard.

ROBERT E. MANLEY.
